LIQUID SOAP DISPENSER

Earl Lavern Morris, Whittier, Calif., assignor to Acorn Engineering Co., City of Industry, Calif.

Filed Apr. 14, 1975, Ser. No. 568,035

Term of patent 14 years

Int. Cl. D6—06

U.S. Cl. D6—95

FIG. 1

FIG. 2

FIG. 3

FIG. 1 is a perspective view of a liquid soap dispenser showing my new design;

FIG. 2 is a side elevational view thereof; and
FIG. 3 is a bottom plan view thereof.

The fragmentary broken line representation of a lavatory in FIG. 1 is for purposes of illustration only.

I claim:

The ornamental design for a liquid soap dispenser, substantially as shown and described.
